INFLATED AERIAL TOY

Jerome H. Lemelson, Perth Amboy, N. J.

Application May 22, 1953, Serial No. 356,864

3 Claims. (Cl. 46—89)

The present invention relates to an inflatable toy, and in particular to a flying balloon toy which is aerodynamically stable such that it may be projected into the air by the user to assume a glide path. This is a continuation-in-part of my copending application Serial No. 314,899 filed October 15, 1952 and entitled Educational Toys.

It is among the objects of the present invention to provide an improved constructional toy which is large and relatively inexpensive for its size.

It is a further object of the present invention to provide a flying toy which is simple in structure, easy to package, comparatively cheap and exceptionally safe in use.

In accordance with an illustrative embodiment demonstrating features of the present invention a toy is provided which is capable of free flight which includes an elongated inflated body of yieldable material and having a nose and a tail. Flight stabilizing means are operatively connected to the body adjacent the tail and include fins extending radially outwardly of the body. A weight is secured to the nose of the body. The flight-stabilizing means and the weights are arranged to cause the body to assume a stable flight path when the toy is projected into the air. In use, the toy is thrust into the air and will traverse a flight path. If during such flight, the toy comes into contact with an object or a person, the yieldable characteristics of the body cushion the object or person against possible injury.

The above brief description, as well as further objects, features and advantages of the present invention will be best appreciated by reference to the following detailed description which makes reference to the drawing wherein:

Fig. 1 shows in front elevation a constructional toy embodying features of the present invention; and

Fig. 2 is an end elevation taken from the right of Fig. 1.

Referring now specifically to the drawing, there is shown a balloon gliding action toy which includes an oblong inflated body 10 having three or more guide wings or fins 25 secured to the inflated balloon body 10 by the use of pressure-sensitive tape 27, cement, or a similar adhesive. Each of the guide wings or fins 25 has two or more tabs 26 which are secured to the inflated balloon body 10 to the fins 25 of the body. Preferably the assembly fins 25 form a symmetrical pattern, when the inflated balloon body 10 is viewed from its ends.

2

A weight 28 is secured to the front end of the balloon body by a length of pressure-sensitive tape, cement or the like to provide a balance to offset the weight of the fins. By the application of the correct weight to the nose of the balloon body and appropriate fins 25 to the tail of the body the toy may be arranged to assume a stable flight path when projected into the air. It is not uncommon for the toy to glide distances of the order of fifty feet or more.

10 A latitude of modification and substitution is intended in the foregoing disclosure, and in certain instances some features of the invention will be used without a corresponding use of other features. Accordingly it is appropriate that the appended claims be construed broadly and in a manner consistent with the spirit and scope of the invention.

Having thus described the invention what I claim is:

1. A balloon toy comprising in combination an oblong inflated body of yieldable material, the ratio of length to diameter of said body being greater than six to one, thin sheet guiding fins extending outwardly from said body near one end thereof, and a weight secured to the other end of said body, said weight being sufficient to balance the balloon properly so that it traverses a gliding path through the atmosphere, said guiding fins serving to stabilize said body in flight.

2. A toy for free flight comprising an elongated inflated body of yieldable material having a nose and tail, flight stabilizing means operatively connected to said body adjacent said tail and including fins extending radially outwardly of said body, and a weight secured to the nose of said body, said flight stabilizing means and said weight being arranged to cause said body to assume a stable flight path when said toy is projected into the air.

3. A toy for free flight comprising an elongated inflated body of yieldable material having a nose and tail, flight stabilizing means operatively connected to said body adjacent said tail and including radially extending fins arranged in a symmetrical pattern about said tail and projecting outwardly beyond the outline of said body, and a weight secured to the nose of said body, said flight stabilizing means and said weight being arranged to cause said body to assume a stable flight path when said toy is projected into the air.
